UNITED STATES PATENT OFFICE.

WALTER B. SMITH, OF MARLBORO, MASSACHUSETTS.

PUZZLE.

SPECIFICATION forming part of Letters Patent No. 700,573, dated May 20, 1902.

Application filed August 23, 1901. Serial No. 73,044. (No model.)

To all whom it may concern:

Be it known that I, WALTER B. SMITH, residing in Marlboro, county of Middlesex, State of Massachusetts, have invented certain new and useful Improvements in Puzzles; and I do hereby declare the following to be a full and clear description thereof.

My invention relates to puzzles and educational appliances.

10 The object of the present invention is to provide a series of blocks or tablets having a series of designated characters thereon, such as numerals, which may be arranged in such order that upon being added a given sum or result may be deduced.

For this purpose my invention consists in the following construction and combination of parts, which will first be fully described in detail and the patentable novelty therein then 20 set forth and claimed.

In the drawings, Figure 1 represents a perspective view of a device embodying my invention. Fig. 2 is a transverse section of the same.

25 1 represents a box or container adapted to hold a stated number of cubes, blocks, or tablets. The box 1 is preferably of rectangular shape. The series of blocks 2 are preferably of square form upon their faces and may be 30 of any thickness desired. The block 3 is preferably oblong and twice the area of the blocks 2.

In a preferred form I employ ten blocks 2, having the numerals "0," "1," "2," "3," 35 "4," "5," "6," "7," "8," and "9." These blocks are adapted to be inserted in the box at random. The block 3 has the number "100" thereon. The educational feature involved in the appliance is to rearrange the 40 series of blocks 2 within box 1 in double columns, so that when added by two additions the total will be one hundred represented upon the block 3.

I may, if desired, put numerals or other 45 characters upon two, three, four, five, or six faces of the blocks 2, and similarly place upon the block 3 the corresponding sums or characters which the different series of characters when added will produce.

A cheap and efficient method of carrying out my invention is to make the blocks of stained wood, with the characters or figures printed in suitable color thereon. Where only a single face of the series of blocks 2 and 3 are used, the characters or figures are printed on the top surface only.

The solution of the puzzle is obtained by disposing the blocks 5, 6, and 7 at the top of the box in any order in the right-hand column and the figures "1," "3," and "4" in any order at the top of the box in the left-hand column. Below the blocks so arranged, for example, thus—

17	65
35	
46	

are placed the blocks 9 and 8 in the order given, so that the sum and result are

17	70
35	
46	
—	
98	

the 98 being the total of 17, 35, and 46. There 75 remain but two additional blocks 0 and 2, which, being added to 98, give

98	80
02	
—	
100	

which is the solution of the problem. The whole arrangement may be restated as follows:

17	90
35	
46	
—	
98	
02	
—	
100	

What I claim as new, and desire to secure 95 by Letters Patent, is—

In a puzzle, a box containing ten blocks, one for each numeral, adapted to count one

hundred in two additions, blocks 1, 3, 4, 5, 6, 7
being so disposed in two columns that when
added their total will be equal to the blocks
9, 8, in the order stated, and the blocks 0, 2,
5 in the order stated, disposed beneath the
blocks 9, 8, whereby the sum total of 100 is
obtained.

In testimony whereof I have affixed my sig-
nature in the presence of two witnesses.

WALTER B. SMITH.
